(57) **CLAIM**

The ornamental design for a lid for a storage container,
substantially as shown and described.

DESCRIPTION

FIG. 1 is a perspective view of a first embodiment of the “lid for a storage container”, showing my new design;
FIG. 2 is a front side elevation view thereof; the rear side elevation view being a mirror image thereof;

FIG. 3 is a top plan view thereof;

FIG. 4 is a bottom plan view thereof;

FIG. 5 is a right side elevation view thereof; the left side elevation view being a mirror image thereof;

FIG. 6 is a cross-sectional elevation view thereof taken at section line 6-6 in FIG. 3;

FIG. 7 is a perspective view of a second embodiment of the “lid for a storage container”, showing my new design;

FIG. 8 is a front side elevation view thereof; the rear side elevation view being a mirror image thereof;

FIG. 9 is a top plan view thereof;

FIG. 10 is a bottom plan view thereof;

FIG. 11 is a right side elevation view thereof; the left side elevation view being a mirror image thereof;

FIG. 12 is a cross-sectional elevation view thereof taken at section line 12-12 in FIG. 9;

FIG. 13 is a perspective view of a third embodiment of the “lid for a storage container”, showing my new design;

FIG. 14 is a front side elevation view thereof; the rear side elevation view being a mirror image thereof;

FIG. 15 is a top plan view thereof;

FIG. 16 is a bottom plan view thereof;

FIG. 17 is a right side elevation view thereof; the left side elevation view being a mirror image thereof; and,

FIG. 18 is a cross-sectional elevation view thereof taken at section line 12-12 in FIG. 15.

The broken lines in the drawings represent unclaimed portions of the design.
